UNITED STATES PATENT OFFICE.

ADOLPH WEILER, OF NEW YORK, N. Y.

DESIGN FOR A SAFETY-PIN.

SPECIFICATION forming part of Design No. 33,915, dated January 15, 1901.

Application filed December 18, 1900. Serial No. 40,321. Term of patent 3½ years.

To all whom it may concern:

Be it known that I, ADOLPH WEILER, a citizen of the United States, residing at New York, in the county of New York and State of New York, have invented and produced a new and original Design for Safety-Pins, of which the following is a specification, reference being had to the accompanying drawings, forming part thereof.

10 The invention is fully disclosed in the following specification, of which the accompanying drawings form a part, in which—

Figure 1 is a side view of my newly-designed safety-pin, and Fig. 2 an end view thereof 15 looking in the direction of the arrow *a* of Fig. 1.

As shown in the drawings, the leading or material feature of my newly-designed safety-pin consists in a spirally-coiled end portion 20 *a*, which connects the back *b* with the pin portion *c*, and in the convoluted coil *d* at the end of the back *b*, opposite the coil *a*, at the bottom of which is a forwardly and upwardly directed hook *e*, with which the pointed end

of the pin portion *c* is adapted to engage, as 25 shown at *f*, and adjacent to each end of the spirally-coiled portion *a* is a loop-shaped portion *g*, by means of which the back *b* and the pin portion *c* are connected with the coil *a*, and the hook *e* is loop-shaped in form and is 30 produced by bending the free end of the convoluted coil *d* forwardly and upwardly and then downwardly and backwardly and then upwardly to the point *h*, where it terminates.

Having fully described my invention, what 35 I claim as new, and desire to secure by Letters Patent, is—

The design for a safety-pin as herein shown and described.

In testimony that I claim the foregoing as 40 my invention I have signed my name, in presence of the subscribing witnesses, this 17th day of December, 1900.

ADOLPH WEILER.
